UNITED STATES PATENT OFFICE.

JOHN HERMAN BRETHAUER, OF WESTCHESTER, NEW YORK.

OPERATING SOUNDERS.

1,386,763.

Specification of Letters Patent. Patented Aug. 9, 1921.

Application filed September 20, 1920. Serial No. 411,373.

To all whom it may concern:

Be it known that I, JOHN HERMAN BRETHAUER, a citizen of the United States, and a resident of Westchester, county of Bronx, 5 city and State of New York, have invented certain new and useful Improvements in Operating Sounders, of which the following is a specification.

While applicable to all motors and engines, 10 stationary or mobile, in which a partial vacuum is created incidental to the operation thereof, my improvements are especially adapted to internal combustion motors, and particularly to those used for the propulsion 15 of automobiles and other vehicles, whether land or marine.

The distinctive feature of my invention consists essentially in utilizing the partial 20 vacuum incidentally created during the operation of a motor (taking the latter term in its broader sense) to actuate a sounding device by a current of atmospheric air, inducted or sucked through said sounding device by means of said motor vacuum as hereinafter more fully set forth,—subsidiary 25 features relating to certain minor details involved in the practical application of the principle stated, whereby effective results are attained, and provision made for the regulation 30 of the tone and pitch of the sounding medium.

In the accompanying drawings,

Figure 1, is a top view of a portion of a hydrocarbon or internal combustion motor 35 illustrating the practical application of the essential features of my invention;

Fig. 2, is an elevation of the parts shown in Fig. 1;

Fig. 3, is an elevation, upon a larger scale, 40 of a sounding device and means for controlling same, adapted to my purpose;

Fig. 4, is a sectional elevation thereof, taken upon plane of line 4—4, Fig. 3;

Fig. 5, is a transverse section taken upon 45 plane of line 5—5, Figs. 3 and 4;

Fig. 6, is a sectional detail taken upon plane of line 6—6, Fig. 5;

Fig. 7, is a perspective detail of one of the reed jaw plates;

Fig. 8, is a sectional detail showing one of 50 the tension screws and adjacent parts on a larger scale.

I herein show and describe my invention as adapted to an internal combustion engine or motor of the multiple cylinder type, 55 with the understanding that I do not limit

myself thereto in the abstract, since the principle involved is adaptable, as heretofore intimated, to any engine or motor, the operation of which involves the creation of an available partial vacuum,—*i. e.*, having a chamber or part in the casing in which the internal pressure is reduced below that of the extraneous atmosphere.

Thus in Figs. 1 and 2, of the drawings, I 65 show by way of exemplification, the carbureter C, and intake manifold C', of a plural cylinder gas motor M, of ordinary and well known construction and operation, it being understood that the intake manifold C', 70 communicates in the usual manner with the inlet valves which admit the admixture of fuel gas and air to the compression and combustion chambers of the piston cylinders, the suction created by the intake strokes of the 75 pistons creating and maintaining a partial vacuum within said manifold C', as and for reasons well known in the art. In the case of multiple cylinder internal combustion engines this partial vacuum in the intake manifold 80 is practically continuously uniform, and reliable for the purpose for which I make it available,—*i. e.*,—for the actuation, by atmospheric air induction, of a suitable sounding device S, duct-connected as at d, 85 with said intake manifold C'.

Obviously various forms and constructions of sounding devices S, may be utilized for the purpose, provided they are adapted to be actuated by air induction, so that I do 90 not limit myself in this respect. In the drawings, by way of exemplification, I have shown a simple form of sounding device of the horn type, provided with a vibratory element e, consisting of what may be designated as a reed plate positioned transversely with relation to an inlet port i, constituted by the inner end of pipe or duct d', the outer extremity of which is screw-connected with a control valve K, which is interposed between it and the pipe or duct d, which connects directly with the manifold C', as aforesaid,—said control valve K, being manipulated as required by a connection rod k, extending into available proximity to the normal position of the operator.

Any desired form and construction of control valve K, may be used for the purpose, provided it is adapted to open and close, or otherwise regulate, communication between 110 the sounding device S, and the intake manifold C'. The duct d, communicating di-

rectly with the latter, may be of less diameter than the inlet duct d' , because the latter must afford an area of inlet i , commensurate with the requirements of the vibratory sounding element e . Thus the inlet duct d' , constitutes practically an attenuation chamber interposed between the inlet port i , and the control valve K , which attenuation chamber tends constantly to neutralize any variation or fluctuation in degree of vacuum within the intake manifold C' , and prevent the clogging of the sounding element e , that might otherwise occur if it were exposed suddenly and directly to the full inductive force of the motor vacuum suction.

In order to regulate the position of the inlet port i , with accuracy with relation to the vibratory sounding element e , provision is made for adjustment in this respect. Thus the inlet duct d' , may be made adjustable with relation to the sounding element e , or vice versa. In the construction shown in the drawings either alternative may be resorted to since the horn h , is supported on a flanged base b , the hub b' , of which is female screw threaded to fit and engage with a peripheral thread on said inlet duct d' —the vibratory element e , being rigidly attached to the horn h . Hence by rotating the horn h , in one direction or the other, the said vibratory element e , may be positioned with accuracy with relation to the inlet port i , so as to augment or reduce the volume of air admitted and sound produced, as required.

The pitch of the sound produced by the induction of air is regulated by the tension to which said vibrating element is subjected. To provide for this the ends of said vibratory element e , are clamped between serrated jaw plates j , j , (see Figs. 5, 6, and 7) mounted on the inner ends of adjustable supporting and tension screws a , a , journaled in fibrous insulating bushings h' , h' , inserted for the purpose in the sides of the horn h —said bushings h' , h' , preventing the transmission of sound vibrations from the sounding element e , through said tension and supporting screws, a , to the horn, which is usually metallic. By this means the element e is drawn more or less taut by means of the screw and thus the tension of such element is adjusted.

It is to be understood that by the term "sounding element" as herein used I mean to designate any element adapted to produce sound vibrations by means of an inductive current of atmospheric air superin-

duced by motor-created partial vacuum substantially as herein set forth.

The air admitted to the intake manifold C' , through my inductive sounding device S , is relatively so small in volume as to be negligible. As a matter of fact it usually is efficacious in promoting more perfect combustion within the motor, because as a rule the admixture of air and hydrocarbon derived from the carburetor is too rich in hydrocarbon, so that my system of inductive sounding may be designated as self-supporting in that it does not detract from, but rather tends to add to, the power and efficiency of the motor.

Another advantage attained by my system of inductive sounding is that a minimum amount of power is required for the purpose because the sounding element is actuated by atmospheric pressure and not against it, as heretofore. In other words, I utilize the fourteen pounds normal pressure of the atmosphere instead of wasting power in overcoming same.

Furthermore my system is conducive to simplicity and cheapness of construction and installing of signaling means,—the essential operative parts being few and not liable to derangement by use.

What I claim as my invention and desire to secure by Letters Patent is,

1. A signal device of the character designated, comprising a horn, a vibratory sounding element located therein, and an air induction conduit having an inlet port positioned in cooperative relation to said sounding element, together with means for adjusting the distance between said sounding element and said air inlet port and means attached to opposite points of said element for regulating the tension of said sounding element, for the purpose described.

2. A signal device of the character designated, comprising a horn, a vibratory sounding element located therein, and an induction conduit having an inlet port positioned in cooperative relation to said sounding element, together with means for adjusting the distance between said sounding element and said air inlet port, serrated members between which opposite portions of said sounding element are clamped, and means connected to said members for supporting and tensioning the sounding element.

JOHN HERMAN BRETTHAUER.
